(57) **CLAIM**

The ornamental design for a folding quadcopter, as shown and described.

DESCRIPTION

FIG. 1 is a perspective view of a folding quadcopter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the folding quadcopter where the folding quadcopter is in a folded state; and,

FIG. 10 is an enlarged view of portion 10 shown in FIG. 2. The evenly spaced broken lines in the drawings depict portions of the folding quadcopter that form no part of the claimed design; the dash-dot-dash broken lines are for annotation purposes only and from no part thereof.
